CONTAINER OPENING DEVICE

John D. Webber, Bayonne, N. J., assignor to
Cemco Engineering and Manufacturing Cor-
poration, New York, N. Y., a corporation of
New York

Application June 22, 1933, Serial No. 677,001

5 Claims. (Cl. 221—23)

This invention relates to container opening devices, and particularly to a device which is provided with a pair of spaced piercing knives and a locating rim to guide the knives into proper positions upon a container to be opened, a spout being preferably also provided so that the opening device may be used as a pouring funnel after a container has been opened preparatory to pouring out its contents.

10 The main object of my invention is to provide an opening device of the character indicated which is simple and reliable to use in opening metal or other containers of given sizes, in order to quickly render it possible to pour out the contents of such containers for use.

Another object is to provide such an opening device for containers with two spaced knives in order to simultaneously pierce two apertures in the top of a container, one resulting aperture being proportioned and intended for pouring the contents, while the other resulting aperture is proportioned and intended to serve as an air vent.

A further object is to provide the container 25 opener with a rim which both guides the knives simultaneously into position upon the top of a container, and also serves as a protection for the knives by preventing accidental contact thereof with other objects than those intended.

30 A still further object is to have a pouring spout upon the opening device, so that the contents of an opened can may be poured into the device when the latter is in inverted position with the spout directed downward into a receiving vessel, etc., the present device then serving as a pouring funnel.

Yet another object is to render the opening device particularly comfortable to the hand so as to present an excellent grip therefor by both 40 convexing the top of said device and locating the spout or pouring opening thereof to one side.

It is also an object of the invention to have a 45 shiftable disk or closure member within the top of the device, provided with at least one opening which in one position of the disk registers with the pouring opening or spout of said device while in all other positions, the disk obstructs said pouring opening and serves as a closure therefor.

50 It should be added that it is likewise an object to provide the present device with a removable spout, and then to have in the closure disk just previously referred to, not merely a single aperture to register in one position of the disk, with

the spout opening, but also a second aperture spaced from the first, which will register with the spout in another position of said disk and is of a sufficient size to allow of withdrawal and removal of the spout from within the device. 5

Other objects and the several advantages inherent in my invention and accruing from its use will appear more fully in detail as this specification proceeds.

In the accompanying drawings forming part 10 hereof,

Fig. 1 is a side elevation of a container opening device made according to one form of my invention and embodying some of the important features thereof. 15

Fig. 2 is another view of the same device as seen from beneath the same.

Fig. 3 is a vertical transverse section of the device on line III—III of Fig. 1. 20

Fig. 4 is a fragmentary section of a modification of the spout.

Fig. 5 is a top plan view of the spout alone of Figs. 1, 2 and 3.

Fig. 6 is a side elevation of the same.

Fig. 7 is a sectional view of an opening device 25 which is a modification of that illustrated in Fig. 1, and is both made according to the preferred form of the invention and embodies substantially all of the salient features and advantages thereof. 30

Fig. 8 is another view of the device of Fig. 7 as seen from beneath the same.

Fig. 9 is a section of the device of Fig. 1, and as indicated in broken lines, also of Fig. 7, when the device is in position upon a container after 35 said device has been pressed down into operated position and the knives have pierced the top of the container the latter being also shown in fragmentary manner and merely indicated by dotted lines. 40

Fig. 10 shows a side elevation of the closure disk which forms an interior part of the device of Fig. 7 and carries the knives thereof.

Fig. 11 illustrates by way of perspective, one 45 of the various ways in which the present opening device may be used after having pierced the pouring and air vent apertures in a container, the device being here used as a funnel or the like.

Throughout the views, the same reference numerals indicate the same or corresponding 50 parts.

It is a matter of common observation that there is a growing tendency to market and dispense in more or less standardized packages or containers all kinds of marketable products which 55

in any manner lend themselves to such handling. This is also true in the case of oils, paints, glue, syrups, fruits, vegetables and other more or less liquid or fluid bodies or powdered and granulated materials, and even includes chemicals, and more often, such materials are put up in paper or metal cans, the latter being preferably permanently sealed. Such sealed products are usually of better grade than other similar products, and the fact that they are thus packaged under an effective seal against the atmosphere and against substitution or loss, makes such products particularly saleable and desirable, provided that they are rendered easily and quickly available when desired, despite the nature of the sealed container holding them.

It is in order to render such products instantly available at will, and with the foregoing and other objects in view that the present invention has been designed.

Hence, in the practice of my invention, a container-opening device, generally indicated by 1, is formed with a locating rim or skirt 2, surmounted by a top 3 which is preferably convex 25 in form in order to present a comfortable and efficient grip for the palm of an operator's hand. The interior diameter of the rim 2 is of such size as to easily pass down upon metal or other containers such as tin cans of a given size, but without very great play. Within the top 3, and spaced within the rim, as well as from each other, are a pair of piercing knives 4 and 5, the same being preferably spaced as far apart as possible, that is diametrically opposite. The reason for this is 30 that it is desired to have the one resulting aperture close to one edge in the top of the container, and the other resulting aperture close to the opposite edge in said top. In addition, the knife 4 is designed to be considerably larger than the other knife 5, in order to form a pouring aperture for the fluid contents of the container, while knife 5 is intended to form an air vent to allow air to enter and replace the contents while the latter are being poured out for use. The 35 manner of fastening the knives into position will be pointed out further on.

Before considering the manner of using the knives, it may be well to note a further feature of the device found in the spout or pouring tube 8 with which the device is also furnished. This tube or spout is preferably tapered, and as it is most convenient for all around use to have the spout removable, it is normally thrust from within through an aperture 10 in top portion 3 of the device and is provided with a flange 9 at the lower extremity to serve as a stop against the inner face of the top portion 3. The spout should be a tight fit so as to remain in position during use, but is quite easily removed by pushing it inward and then inverting and thrusting it inward into aperture 10, when it will project into the interior of the device and render the same more compact in idle condition thereof.

On the other hand, the spout could be permanently soldered, brazed or welded into its normal useful position, as in some cases it might be desirable to have the spout permanently fixed. When the latter fixed position is desired, it is decidedly more simple to utilize the material displaced in forming aperture 10 by striking this up in the dies to form a spout 12 which is integral with the top portion 3 as indicated in Fig. 4, or with the side rim 2.

Nevertheless, in each case, the spout is preferably located in an eccentric position upon the

convex top portion of the device in order that the hand will not be obstructed when gripping the device for use, which will become obvious when the device is to be used for opening containers. But the main purpose of the eccentric position of the spout is to facilitate pouring oil, for example, into more or less inaccessible lubricating openings upon internal combustion engines and the like.

It is also evident that the dished condition of the top portion or pouring basin 3, as well as the eccentric position of the pouring spout render it possible to pour out the oil upon the basin and will tend to cause any dirt in the oil or fragment of any material which may accidentally have gotten into the oil to settle and be retained upon the basin at the deepest central portion thereof. It is also quite easy to note the progress of the pouring and drainage of the oil upon and from said device because of the presence of the pouring basin.

Now, if a metal can or container 20 such as indicated in Figs. 9 and 11 is to be opened and emptied, the device 1 of the invention described thus far is placed upon the can so that the rim 2 25 envelopes the upper edge 21 of the container, in which position the knives 4 and 5 are located above the top 22 immediately within the edge 21. If the hand is then pressed down upon the device, with the palm lying conformably upon the convex portion or top portion 3 thereof, and the device forced down until the container edge 21 strikes the interior of the top portion 3, then knife 4 and also knife 5 will pierce the top of the container in two spaced positions and curl back a pair of 30 tongues 23 and 24, producing a pouring aperture 25 and an air vent or aperture 26, respectively. If the device 1 is now removed from the can and inverted, and the spout 8 located directly over a lubrication opening 28 of an engine 29, or over 40 an oil dispensing or lubricating can, etc., as indicated in Fig. 11, then it is but necessary to tilt container 20 and hold it above the opening device 1 so that aperture 25 is at the lowest point within edge 21 and adjacent to the device 1, 45 when the liquid contents will readily pour out into the device 1 as indicated at 27, as the device in this position serves in the role of a funnel or the like. Due to the presence and position of the air vent 26 at the highest point in the top 21 of 50 the can in the position for pouring clearly shown in Fig. 11, while pouring aperture 25 is in the lowest possible position, the entire contents of the can will easily be drained to the last drop. The tongues 23 and 24 also enhance the tendency 55 to complete drainage of the can, as they are curled inward toward the center of the top 21 and thus do not in any manner obstruct the outward flow of fluid from aperture 25, or the inward rush of air entering through aperture 26 to 60 replace the fluid within the can.

In the knives illustrated, there are two straight cutting edges which will in each case produce an aperture in the container top of triangular form. This is an advantage, both in simplifying 65 manufacture of the knives, and causing the stream of fluid issuing from the same while emptying the container to be so readily directed to the opening of the object into which the fluid is intended to be poured, so that it is even possible to pour directly into said opening without using the present device intermediately as a pouring funnel. Naturally, any other practical form of knife could be used, such as arcuate, square, oval or any other form, the apertures cut in the 75

5 container top being correspondingly semicircular, square, oval etc., but in any case, the aperture thus produced is intended to be slightly smaller in area than the cross section area of the opening 11 of spout 8 or opening 13 of the integral spout 12, in order to allow speedy draining of device 1 and prevent flooding thereof.

10 It is also possible to use the device as a closure for a container after having opened the same by piercing the pouring and venting apertures, which feature is inherent in the preferred form of the invention illustrated in Fig. 7 onward. In this form of the device, the top portion 3 is first provided with an interior recess 14 about the 15 aperture 10 in order to accommodate flange 9 of the spout 8. In other words, the flange of the spout is thus drawn up into the interior general surface profile of top portion 3 in order that said flange will not form an obstruction, as will immediately be explained.

20 Within the device, a disk 16 which conforms with the concave inner face, or as it may also be termed, the dished pouring basin, of the top portion 3, is mounted in sliding contact with said concave inner face and retained in position by the pivot 15 which is riveted to said top portion 3 and passes through the central aperture 19 of the disk. Hence, the disk is rotatable within the top portion of the device about the pivot, and 25 remains continuously in full contact with the inner face of said top while clearing flange 9 of the spout, and thus itself virtually forms a pouring basin located upon the top portion 3 and solely connected thereto by means of the central 30 rivet. In this disk, a pair of apertures 17 and 18 are formed in spaced positions, but with their centers equally distant from the central pivot 15, the distance corresponding with the center distance of the aperture 10 and spout 8 from the 35 same pivot. The immediate result is that, by turning the disk 16 about its pivot, it is possible to register either aperture 17 or 18 with the top aperture 10, and of course, with the bottom of opening 11 in the spout.

40 In this form of the invention, the knives 4 and 5 are not secured to the top 3 directly, but instead to the dished underside of the disk 16. These knives are preferably fastened rigidly by lugs such as 6, 6 in the case of knife 4, and 45 by lugs 1, 1 in the case of knife 5 to the disk, which latter may thus be termed a knife disc. On the form of the invention shown in the first 50 three figures, the knives are, of course, attached by their lugs directly to the top portion 3 of the device 1. But in either case the lugs may be brazed, soldered, riveted or welded to the part to which the knives are to be secured, or may be fastened in any other manner known to the art. Naturally the lugs may be omitted entirely and 55 the knives directly welded by spot welding to said part intended to carry them, or be integral therewith.

60 Returning now to the preferred form illustrated in Figs. 7, 8 and 9, and partly shown in Fig. 10 the aperture 17 in disk 16 is designed to correspond in size with the lower extremity of the spout opening 11, while covering the flange 9 of said spout and thereby both retaining the spout 65 positively in position, and also allowing any fluid poured into the device to immediately flow out through said aperture 17 and the spout. The other aperture 18 is designed to be slightly greater than the outside diameter of the flange so that, 70 when the disk is turned about its pivot to register

75 said aperture with the bottom of the spout, the latter may be pushed inward through top portion 3 in order to remove the spout, when it will be found to readily pass through aperture 18 in said disk. Of course, when the spout is in 5 position with the disk turned to a position in which neither aperture registers with the spout opening, the disk serves as a closure for the spout. Under such circumstances, after having poured only a portion of the contents from a container 10 which has been pierced by the knives, as already described, it is only necessary to replace the device upon the container while reinserting the knives into their respective apertures, when the device with the disk 16 closing the spout will 15 form a closure or cover for the container and will prevent dust and dirt from entering and contaminating the contents. It may be noted that when the device thus forms a cover, while the knives remain in the container apertures, 20 it is possible to turn the disk to register aperture 17 of the same with the spout opening by turning the outer portion of the device in one direction while turning the container in the opposite direction, or even holding it still, because the knives 25 in this form are secured to the disk and force it to turn or remain stationary with the container. If the container is then tilted with the device in position and the spout open, it is possible to 30 drain the container by the spout without removing the device from said container. Other modes of using the device are also possible. For example, the spout may be removed and the device used by pouring fluid from a container into the same and allowing the fluid to flow out directly through aperture 10 in the case of the form shown in Figs. 1, 2 and 3, and out through either aperture 17 or 18 of the disk and also through aperture 10 of the top portion 3 in the 35 form of Figs. 7, 8 and 9.

40 The device may be made of any suitable material, as for example, of bakelite, ebonite, metal sheet or castings, etc. Various modifications may be resorted to, and parts used without others. For example, instead of the interior disk 16, an 45 outside sliding lid or a cover may be provided for the device, covering the opening 10 in the top portion 3, and also closing the spout, if inverted. The purpose of such a cover would be to provide a solid or imperforate top for the device, 50 which cover in addition may serve as an interchangeable fitting upon which advertisements and the like may be lithographed or otherwise applied while the cover is interchangeable independently 55 of the device per se, the generally flat top thereof, however providing upon the cover an ample space for such advertising matter.

Having now fully described my invention, I claim:—

1. In a container opening device adapted for 60 use as a pouring funnel and having a pouring means to direct the flow of a liquid from said device, as well as a continuous peripheral guiding rim adapted to guide the device into proper position upon the container to be opened, means forming in combination with the exterior of said continuous guiding rim an efficient exterior hand hold for said device, comprising a convexly arcuate top portion integral with said guiding rim, having the pouring means eccentrically disposed 65 upon the same to provide clearance for the fingers and enhance the manual hold upon the device when using the same to open said container, and an interiorly arcuately concave disk pivoted to and corresponding in form with the 70

interior concave surface of the exteriorly convex top portion of the device, serving as a support for at least one piercing knife for opening the container and by virtue of its concave shape forming in combination with the continuous guiding rim an efficient pouring basin of practical capacity, which concave disk has an apertured portion and is rotatable about its pivotal mounting to bring said apertured portion in one rotated position into register with the pouring means and also further rotatable to close said pouring means and allow the device to be replaced upon the container after the same has been opened in order to form a closure cap thereon.

2. In a container opening device adapted for use as a pouring funnel and having a pouring spout to direct the flow of a liquid from said device, as well as a continuous peripheral guiding rim adapted to guide the device into proper position upon the container to be opened, means forming in combination with the exterior of said continuous guiding rim an efficient exterior hand hold for said device, comprising a convexly arcuate top portion integral with said continuous guiding rim, having the pouring spout eccentrically disposed upon said top portion to provide clearance for the fingers and enhance the manual hold upon the device when using the same to open said container, which top portion is interiorly of an arcuate concave form, and an interiorly arcuately concave disk pivoted to and corresponding in form with the interior concave surface of the exteriorly convex top portion of the device, which concave disk, by virtue of its concave shape, forms in combination with the continuous guiding rim, an efficient and capacious pouring basin and both has an apertured portion and is rotatable to one position wherein said apertured portion registers with said spout and to other positions wherein said disk forms a closure for said spout, and further forms a support for a pair of spaced piercing knives fixed in opposite spaced positions on the edge portions of said disk within said rim for piercing the top of the container when the device is applied thereon.

3. In a container opening device adapted for use upon cylindrical containers and having a con-

tinuous peripheral guiding rim adapted to guide the device into proper position upon the container to be opened, means forming in combination with the exterior of said continuous guiding rim an efficient exterior hand hold for said device, comprising a convexly arcuate top portion integral with said continuous guiding rim, which top portion interiorly comprises a concavely arcuate means cooperating with the guiding rim to form an efficient pouring basin of practical capacity for receiving the liquid poured into the device from the container, there being cutting means spaced within said guiding rim upon said concavely arcuate means for cutting into the top of the container to open the same, and a disc permanently retained within said concavely arcuate means and directly carrying said cutting means so as to serve as a distinct mounting therefor in said device.

4. A container opening device for use upon a substantially cylindrical container, comprising a cup-like cover adapted to fit snugly over the container to be opened, a rotatable disc secured upon the inside of said cover and adapted to overlie said container when the device is in position thereon, and a knife assembly mounted directly upon said disc so that when the knives are placed in position for opening the container, simple pressure will be effective to cause said knives to puncture said container and will allow the cover to be freely rotated.

5. A container opening device for use upon one end of a metal container or the like, comprising a covering top member having means upon the periphery thereof adapting said top member to be properly located over and fitted upon the container to be opened, a rotatable disc secured upon the inside of said top member and adapted to overlie said end of the container when the device is in position thereon, and piercing means mounted directly upon said disc so that when the piercing means are placed in position for opening the container, simple pressure will be effective to cause said piercing means to puncture said container and allow the top member to be freely rotated upon said disc.

JOHN D. WEBBER.
